UNITED STATES PATENT OFFICE.

JOHN L. ESLINGER, OF TUCUMCARI, NEW MEXICO, ASSIGNOR OF ONE-HALF TO
CHARLES L. McCRAE, OF TUCUMCARI, NEW MEXICO.

AUTOMATIC PUMP-REGULATOR.

1,210,285.

Specification of Letters Patent. Patented Dec. 26, 1916.

Application filed November 18, 1913. Serial No. 801,735.

To all whom it may concern:

Be it known that I, JOHN L. ESLINGER, a citizen of the United States, residing at Tucumcari, in the county of Quay and State 5 of New Mexico, have invented new and useful Improvements in Automatic Pump-Regulators, of which the following is a specification.

This invention relates to feed-water regulators for steam boilers, the object in view being to provide means for automatically regulating the amount of water fed to the boiler so as to maintain a certain level of water in the boiler irrespective of the load 10 imposed thereon, the water level being maintained by the action of a feed-water pump which is controlled by the level of water contained in a reservoir forming an extension of the water space in the boiler.

With the above and other objects in view, the invention consists in the construction, combination and arrangement of parts, as will hereinafter be more fully described, illustrated and claimed.

In the accompanying drawings: Figure 1 is a side elevation partly in section of the reservoir, showing upper and lower connections to the steam boiler. Fig. 2 is a plan view of the same. Fig. 3 is a side elevation 25 on a reduced scale showing the application of the device to a boiler and pump.

In carrying out the present invention, I employ a reservoir A of any suitable capacity in accordance with the capacity of the 30 boiler in connection with which the reservoir is used.

The reservoir A is preferably formed in the shape illustrated in the plan view Fig. 2 so as to provide for the reception therein 35

40 of a rising and falling float B which moves upwardly and downwardly in accordance with the level of water contained in the reservoir A, said reservoir being connected with the boiler by means of an upper steam pipe connection a and a lower water connection b, the reservoir therefore having a water space and a steam space corresponding in level with the water and steam spaces of the boiler.

45 The float B is mounted at one end of a float lever C the same being formed with a slot c' to receive a pin c on a support or

bracket D fastened to the inside of the reservoir A as shown in Fig. 1. The support D is shown as provided with a number of 55 perforations d to admit of the adjustment of the pin c thereby correspondingly adjusting the height of the float B to provide for the earlier or later operation of the steam valve controlled by the float B. Connected 60 pivotally to the opposite end of the float lever C is a rod E which extends upwardly through a guide F within the reservoir and also through a stuffing box H at the top of the reservoir, said rod being connected pivotally to a steam valve stem or operating rod G, said valve being located in the lead e between the steam space of the boiler and the pump I which forces the water to the 65 boiler.

70 From the foregoing description it will be understood that when the water is at the desired level in the boiler, the same level of water in the reservoir will hold the float B elevated and very little or no steam will be admitted to the pump. Therefore, 75 no water will be pumped into the boiler at this time. As soon as the level of water in the boiler falls, the float B will correspondingly fall thereby operating the stem G to 80 open the pump controlling steam valve. This allows steam to pass to the pump and the latter operates immediately to force water to the boiler. The amount of steam 85 passing to the pump thus varies in accordance with the level of water in the boiler and reservoir. The higher the level in said boiler and reservoir, the less steam will there be admitted to operate the pump thus making the device entirely automatic in operation.

90 What I claim is:

In a device of the class described, in combination, a cylinder, a pair of brackets secured upon the inner wall of said cylinder, 95 one of said brackets forming a guide, the other bracket being L-shaped, a rod passing through said guide and projecting above said cylinder, said L-shaped bracket being provided with a plurality of openings upon 100 its vertical arm, a pin passing through one of said openings, a lever pivoted upon said pin and also upon the lower end of said rod, a float secured to said lever, a plate closing

the top of said cylinder and having a stuffing box through which said rod passes, an arm extending from the side of said cylinder above said top plate, and a lever pivoted upon this last named arm between its ends and also pivoted to said rod at the upper end of the latter.

In testimony whereof I affix my signature in presence of two witnesses.

JOHN L. ESLINGER.
